UNITED STATES PATENT OFFICE.

AUGUST THOMAS, OF SALT LAKE CITY, UTAH.

DEVICE FOR TURNING CRANK-PINS ON ENGINE-SHAFTS.

1,114,068.

Specification of Letters Patent. Patented Oct. 20, 1914.

Application filed May 25, 1914. Serial No. 840,939.

To all whom it may concern:

Be it known that I, AUGUST THOMAS, a citizen of Germany, residing at Salt Lake City, in the county of Salt Lake and State 5 of Utah, have invented certain new and useful Improvements in Devices for Turning Crank-Pins on Engine-Shafts, of which the following is a specification.

My invention relates to devices for turning crank pins on the crank shafts of engines, and has for its object to provide a simple and efficient device which may be secured on a turning lathe of the ordinary make, by which a crank pin may be turned 15 on the crank shaft of an engine without removing the shaft from the lathe or changing the axial point. These objects I accomplish with the device illustrated in the accompanying drawings in which similar letters 20 and numerals of reference indicate like parts throughout the several figures and as described in the specification forming a part of this application and pointed out in the appended claims.

25 In the drawings in which I have shown a substantial embodiment of my invention, Figure 1 is a fragmentary view in elevation of a turning lathe with my device secured thereon in position to turn one of the four 30 crank pins of the crank shaft held in said lathe. Fig. 2 is a side elevation of the device, looking in the direction of the arrow and on line α α of Fig. 1, with the crank shaft given one half turn. The position of 35 the device as shown in Fig. 1 is herein shown in dotted lines. Fig. 3 is a detail in side elevation of one element of the combined tool rest. Fig. 4 is a front elevation of the same and Fig. 5 a plan view. Fig. 6 is a detail 40 in side elevation of the tool stock housing. Fig. 7 is a front elevation of the same. Fig. 8 is a horizontal section on line y y of Fig. 6. Fig. 9 is a detail in side elevation of the centering guide case. Fig. 10 is a plan view 45 of the same. Fig. 11 is a detail in side elevation of one of the gripping jaws. Fig. 12 is a detail in side elevation of the opposing jaw. Fig. 13 is an end view of either of said gripping jaws. Fig. 14 is a plan view of 50 the centering case with the gripping jaws removed. Fig. 15 is a detail in side elevation of the same.

My device is intended as an attachment

which may be secured and used on the ordinary lathe by removing the common tool post and fastening the bracket of the standard 3 on the tool rest R by T-bolt 1, the head of which engages the cheeks of said tool rest R the bolt being inserted through the horizontal bracket rib 2. The tool rest element by which the other portions of the device is fastened to the bed of the lathe is indicated as a whole at A, and consists of the two vertical standards 3 and 4 which are spaced apart and secured in parallel relation to each other by the head plates 5.

A circular housing B is slidably carried between and by said standards 3 and 4 and a portion thereof is operated between said standards. Said housing consists of two 70 semi-circular members 7 and 8 suitably fastened together to form a circle of their inner peripheries. Each of said members 7 and 8 has its inner periphery cut to form a V-shaped channel 17 therein. One edge of 75 said member 7 is extended to form a wing 9 which is operable between said standards 3 and 4. On said wing is provided the transversely disposed guide ribs 10 which are operated in V-shaped channels cut in the said 80 standards 3 and 4. The outer end of said wing 9 is laterally flanged to engage the edge of said standard 4. A channel 11 is cut or is provided in one side of said wing and extends as an opening in the said flanged 85 portion, within which channel a tool stock 12 is operated. The cutting tool 13 is secured in said stock 12, and the usual screw feed 14 is provided to adjust said cutting tool to its work. A circular guiding case 15 90 is operated within said housing B, and its peripheric face is given an A-shape as at 31 to engage within the said V-shaped channel 17 cut in the inner periphery of said housing. One portion of said guiding case 15 95 is extended to form a grip case 16, and the face of said case 15 is cut out. Said grip case 16 is given a circular exterior on three sides and is cut out on the other side. The interior of said grip case is cut out in rectangular form as shown in Fig. 9 to receive the shaft gripping elements shown in Figs. 11, 12, and 15. The shaft centering and gripping elements consist of a U-shaped centering case 18 with portions of the sides 100 cut away to form shoulders 21 thereon. Set

screws 22 are provided in the side portions of said centering case to engage the engine shaft by which said shaft is firmly gripped. Centering pointers 23 are also detachably secured on said centering case by means of which the axis of the intended crank pin may be positioned relative to the axis of the shaft. The gripping jaws 24 and 25 are provided to operate within the said centering case by 10 which the shaft is held in position. They are adjusted and held in contact with the said shaft by set screws inserted through the openings 26 and 27.

The assembling and operation of my device is as follows:—The commonly used tool post is removed from the lathe and the vertical standards are fastened on the tool rest R by inserting the T-bolt 1 through the horizontal bracket rib 2, a nut screwed on 20 said bolt will hold said standards vertically in place. The commonly used screw for moving the tool rest transversely across the lathe is removed, this allows the tool rest and said vertical standards 3 and 4 to move 25 back and forth on the lathe as the movements of the other elements of my device and the rotation of the shaft on which the pin is to be turned requires. The said semi-circular members 7 and 8 are fastened together 30 around the said guiding case 15 by the bolts, the A-shaped rib 31 on the peripheric face of said guiding case 15 engaging within the channel 17 in the inner face of said members 7 and 8, this allows 35 free rotation of said centering case within housing B. The said housing B is then inserted between said standards 3 and 4 by removing the upper head plate 5 and inserting the wing 9 between said standards. 40 Said wing is free moving up and down between said standards, this allows free vertical movement of the said housing as the rotation of the shaft requires. The said centering case 18 is inserted within said 45 grip case 16 and said guiding case 15 through the open face of the latter, the shoulders 21 of the centering case 18 engaging the shoulders 20 of the guiding case 15. The gripping jaw 25 is next inserted within 50 the centering case 18 and engaged by a set screw operated through the hole 27.

In using my device the shaft, having a pin thereon to be turned, is centered in the lathe in the usual manner and inserted through the device adjacent the gripping jaw 25. The size of the pin to be turned being predetermined the pointers 23 are set as near the axial center as may be and yet leave the portion of the crank shaft from 60 which the intended crank pin is to be turned free. The distance from the axis of the shaft to the axis of the intended crank pin being known, the device is moved relative

to the said shaft until the centering pointer 23 on the side of said centering case 18 is in lateral alignment with the axis of the intended pin and the other pointer 23 indicates that the pin axis is in its line. The device is then set firmly on the shaft by the other gripping jaw 24 as adjusted by 70 the set screws 26 and 22. The pointers 23 may then be removed, as ordinarily they are in the way when operating the lathe. The tool stock 12 and the cutting tool 13 are then brought into the cutting position by the 75 usual screw feed 14. When the shaft is then rotated the pin will be revolved therearound, and as so revolved the housing B and all the parts of the device will follow the pin in its revolutions, the vertical sliding of the 80 wing portion of the housing between said standards and the horizontal sliding of the tool rests on the lathe carriage allowing such revolutions.

The device is moved longitudinally in the cutting work by the usual movement of the carriage on the bed of the lathe. The U-shaped centering case remains in its fastened position and does not move longitudinally with the cutting elements. 90

Having thus described my invention I desire to secure by Letters Patent and claim:—

1. A device for turning crank pins integral with a crank shaft, comprising a lathe; means for rotating the shaft on its axis; a cutting tool; a carrier for said tool; and means for securing the carrier on the lathe which will allow limited lateral and vertical movement of said carrier, said means consisting of a transversely movable tool rest and a vertically movable housing. 95

2. An attachment for a lathe to turn crank pins integral with a crank shaft, comprising a cutting tool; a carrier for said tool; means to secure said carrier on the lathe which will allow said carrier the same movement as is imparted to the pin, said means consisting of a transversely movable tool rest; a vertically movable housing; and means to guide said carrier longitudinally along the pin, said means consisting of a guide case operable in said housing; and a grip case laterally movable in said guide case. 110

3. An attachment for a lathe to turn crank pins integral with a crank shaft, comprising a cutting tool; a carrier for said tool; a tool rest transversely movable on the lathe; a vertically movable housing; a guide case operable in said housing; a grip case laterally movable in said guide case; and means to detachably fasten said grip case on said shaft. 115

4. An attachment for a turning lathe to turn crank pins integral with a crank shaft, 125

comprising a tool for operating on said pin; a carrier for said tool; a tool rest transversely movable on the lathe; a vertically movable housing; a guide case operable in 5 said housing; a grip case laterally movable in said guide case; and means to detachably fasten said grip case on said shaft.

In testimony whereof I have affixed my signature in presence of two witnesses.

AUGUST THOMAS.
